(57) **CLAIM**

The ornamental design for a combination toothbrush, mouthwash container, and dental floss container, as shown and described.

DESCRIPTION

FIG. 1 is a perspective view of a combination toothbrush, mouthwash container, and dental floss container showing my new design;

FIG. 2 is a top plan view thereof;

FIG. 3 is a side elevation view thereof, the opposite side being a mirror image;

FIG. 4 is a bottom plan view thereof;

FIG. 5 is a right end view thereof;

FIG. 6 is a left end view thereof; and,

FIG. 7 is a fragmentary perspective view thereof, showing the dental floss container flipped open to reveal the mouthwash container's opening.
